United States Patent Office.

WILLIAM J. FRYER, OF WEST TROY, NEW YORK, ASSIGNOR TO HIMSELF
AND JOHN P. WITBECK, OF THE SAME PLACE.

Letters Patent No. 66,317, dated July 2, 1867.

IMPROVEMENT IN PATTERNS FOR CASTING POT-HOLE COVERS.

The Schedule referred to in these Letters Patent and making part of the same.

Be it known that I, WILLIAM J. FRYER, of West Troy, State of New York, have invented a new and useful Method of Constructing Patterns for Mouldings preparatory to casting lips with their cavities to receive handles for the lifting of pot-hole covers, and for analogous uses; and I declare the following specification, with the drawings forming part of the same, to be a full and complete description of my invention.

Figure 1 represents in perspective the pattern of a pot-hole cover with a portion removed in the line of the central vertical section of the lip and cavity.

Figure 2, in perspective, a segment of pattern in the usual position for drawing the pattern after moulding.

Figure 3 represents in plan the upper surface (fractional part) of a pattern with my improvement attached.

Figure 4, the under surface of the same.

Figure 5, in perspective, a segment of the pattern with the near portion in the line of *x y*, fig. 3, removed.

Figure 6, a vertical section through *w z*, fig. 4.

Figure 7, a central vertical section of the core.

Similar letters denote the same parts of the apparatus.

It is well known to moulders that it is impossible, with the patterns now used for moulding pot-hole covers, to prepare the mould in such manner that when the pattern is drawn the core can be put on immediately, and the casting made without some further process to form the lip cavity and leave a space for the metal to form the lip itself, and that the best process at present to permit the drawing of the pattern, is to make that part of it intended to make the impress for the lip and its cavity solid, in the form shown by *a*, fig. 2, and to insert within the space, after the pattern is drawn, a core shaped like *b*. This can be made of prepared sand or other suitable material, but a bright chill of iron, oiled and sanded, is usually employed, which can, from the shape of its cavity, be driven out after the casting is completed. This operation requires great care and expenditure of time in preparing and placing the core, adding materially to the cost of the castings, and it is to obviate this that I propose, by the use of my pattern, which is constructed as follows:

A (figs. 3, 4, and 5,) is the cover-plate; *c c c e* the usual opening for the introduction of the handle, with its chamber *d d* below it, cast with the plate. An extension of the opening *c e* is made through the plate a little wider than itself, extending towards the centre of the plate from *e e* to *f f*. This opening is occupied by a sliding-plate, *B*, of its own length and width. At its outer end a chamber, *g*, (see fig. 5,) is formed, corresponding with and fitting at its end with the edges of *d*, and is of a depth equal to that of the intended lip, so that when the two chambers are placed together they shall form the usual cavity and lip for a handle, as shown. The sliding-plate *B* is as thick as the plate, or nearly so, and at its inner end is entered into a channel or groove, *h f*, cut from the under side of the plate nearly through it, and extending towards the centre sufficiently to permit the slide to move a little further than the distance equal to the depth of the intended lip. The slide is kept up by a thin metal plate, *m*, secured underneath it. It is supported at its outer end by slide-pieces *k k*, fitted along the sides of *d*.

The operation of the apparatus is this: The plate *A* having the chambers *d* and *g* closed upon each other, the pattern is moulded within the flask in the position of fig. 5, (in the usual way,) during which process the chambers become filled with the sand thoroughly rammed into them. The flask being then turned over, the under part of the pattern is moulded within the cope in the position shown in fig. 6. When the cope has been removed the slide with the chamber *g* is to be moved inwards until, as shown in fig. 6, it uncovers the sand moulded within it, when the pattern can be drawn upwards without disturbing the sand, leaving a core standing shaped as shown at fig. 7, with, at *t*, a space for the cast metal to form the required lip. The cope being replaced and the usual adjustments made, the mould is ready to receive the metal.

The superiority of this process over the usual method of casting is manifest. The core being formed of green sand in the usual course of moulding the upper part of the pattern, so as to leave upon the removal of the cope nothing to do in order to permit the drawing of the pattern but to move the slide as described, without any fitting in of separate cores and the previous preparation of the cores, reduces what is now a complex and delicate operation to the footing of ordinary green-sand moulding, effecting a very important saving of time, care, labor, and consequently expenses in the process of casting pot-hole covers.

What I claim as my invention, and desire to secure by Letters Patent, is, in the construction of patterns for moulding pot-hole covers and analogous objects—

The chamber *d*, in combination with the plate *B*, with its chamber *g*, fitted to occupy the cavity *f f*, and to slide within the channel *h*, substantially as described, and for the purposes set forth in this specification.
